MACHINE FOR APPLYING NECKS TO
COLLAPSIBLE TUBES

Frederic Remington, Elizabeth, and Richard A. Tartaglia, East Orange, N. J., assignors to Peerless Tube Company, Bloomfield, N. J., a corporation of New Jersey

Application June 15, 1943, Serial No. 490,870

14 Claims. (Cl. 153—21)

1

This invention relates in particular to a machine for feeding and applying plastic necks to metallic collapsible tube bodies, although in its broader aspects the invention contemplates means for supporting and conveying any of various articles such as collapsible tubes in succession past one or more stations where a part, e. g., a plastic neck, is fed to and secured upon each article in one or more operations.

It has been proposed to form a socket or recess in one end of the body portion of a metallic collapsible tube, insert a threaded neck of plastic material in said socket and swage or squeeze or press the walls of the socket around the neck so as to secure the latter by a firm, liquid-tight joint to the tube body.

One object of the invention is to provide a machine of the general character described which shall comprise a novel and improved construction, combination and arrangement of a support for articles such as collapsible tubes formed of ductile material and having a socket or other portion for attachment thereto of another part such as a neck, means for moving said support to convey said articles in succession past one or more stations, means for feeding and applying one of said parts to said portion of each tube, and means for swaging, squeezing or pressing the material of said articles around said parts to secure the parts on said articles, whereby such parts can be applied to such articles rapidly and relatively inexpensively.

In many cases, especially in applying plastic necks to metallic collapsible tubes, a plurality of operations are required in pressing the material of the articles around the parts being secured thereto, and therefore another object of my invention is to provide a machine of the character above described which shall include a plurality of tools or parts or sets of parts such as dies, each to perform one of said operations, and a common support and actuator therefor arranged in such relation to means for conveying said articles, that one of said operations shall be performed upon one of said articles at the same time that the other operation is being executed upon a preceding or a succeeding article as the case may be, whereby speed and simplicity of operation shall be attained.

It is desirable in such machines that the article conveyor include article holders which move in an endless path or in cycles past said stations, and each article after one of said parts or necks has been secured thereon must be removed from its holder before the latter is returned to the sta-

2

tion at which said parts are supplied. Should an article having one of said necks or parts attached thereto be presented on the conveyor at said part-feeding station, jamming or injury of parts of the machine might occur upon feeding of another part or neck and as a result of operation of the aforesaid tools or dies. Therefore, another object of the invention is to provide novel and improved means for controlling the feeding of said parts or necks such that feeding of the parts shall be prevented or interrupted in case an article having one of said parts thereon inadvertently is presented at said station.

Another object is to provide a novel, improved, simple and reliable construction, combination and arrangement of a device for pushing a part such as a plastic neck into proper relation to a portion of an article such as a socket on the end of a collapsible tube, means for pressing said portion of said article and said part into tight contact with each other, and common means for operating said devices in succession in a continuous operation.

Other objects, advantages and results of the invention will be brought out by the following description in conjunction with the accompanying drawing in which

Figure 1 is a front elevational view of a machine embodying our invention for applying plastic necks to metallic collapsible tubes.

Figure 2 is a side elevational view of the machine.

Figure 3 is a top plan view thereof with portions broken away and shown in section.

Figure 4 is an enlarged fragmentary vertical longitudinal view on the line 4—4 of Figure 1, showing the relationship of the parts during the first step in applying a plastic neck to a collapsible tube.

Figure 5 is a similar view showing the second step in securing the plastic neck to the tube.

Figure 6 is an enlarged horizontal sectional view on the line 6—6 of Figure 1.

Figure 7 is an enlarged transverse vertical sectional view on the line 7—7 of Figure 3.

Figure 8 is a further enlarged fragmentary horizontal sectional view on the line 8—8 of Figure 4.

Figure 9 is a similar view on the line 9—9 of Figure 5.

Figure 10 is an enlarged transverse vertical sectional view on the line 10—10 of Figure 4.

Figure 11 is an enlarged fragmentary vertical sectional view on the line 11—11 of Figure 6.

Figure 12 is a transverse sectional view on the line 12—12 of Figure 11.

Figure 13 is a sectional elevational view of a simple form of a normally open electric switch for the circuit of the control mechanism for the neck feeding apparatus, taken on the line 13—13 of Figure 1.

Figure 14 is a similar view of the normally closed switch for said control mechanism taken on the line 14—14 of Figure 2, and

Figure 15 is a wiring diagram for said mechanism.

Specifically describing the illustrated embodiment of the invention, the machine is shown as including a main frame A upon which is mounted a carrier disc B which has a plurality of dead spindles or supports C for articles such as collapsible tubes D. The carrier is movable so as to convey the articles D in a predetermined path with a step-by-step or intermittent motion and to present them in succession at two operating stations. Each article or tube D has a portion, specifically an annular socket 1 at one end, in which a part such as a plastic neck 2 is to be secured.

At one of said operating stations is apparatus E for feeding the parts or necks, and mechanism F for applying the parts or necks to the tubes D. At the other station is an operating element G for performing another operation on the articles or tubes after they have been operated upon at the first station.

The articles or tubes to be operated upon are placed upon and removed from the holders C by hand.

More specifically, the carrier B comprises a turret disc which is mounted on a shaft 3 which in turn is journaled in the frame A to rotate on a horizontal axis, and the dead spindles C project horizontally from one face of the disc in circumferentially spaced relation. The carrier disc is rotated with an intermittent or step-by-step motion in any suitable manner as by a Geneva gear H which is driven through a train of gears I from a drive shaft K.

The feeding apparatus E comprises a vertical chute 4 in which the necks 2 are arranged in superposed relation so that they will descend by gravity in the chute. The chute has a horizontally disposed lower end which is provided with a discharge opening 5 which registers with an opening 6 in the housing 7 in which the devices F are mounted. A spring detent 8 normally prevents discharge of the necks through the openings 5 and 6 but upon application of sufficient pressure on the lowermost neck to overcome the spring resistance of the detent 8, the detent will be displaced and permit the lowermost neck to pass from the chute. For ejecting the necks from the chute, we have utilized a reciprocating ejector bar 10 which normally is disposed above the lowermost neck in the chute 4. A tension spring 11 normally influences the ejector bar downwardly to eject a neck 2 from the chute, but movement of the ejector bar is controlled by a lever 12 which is pivotally mounted at 13 intermediate its ends on the frame A and has a pin and slot connection 14 at one end with the ejector bar 10. The other end of the lever 12 carries a roller 15 which follows a cam 16 that is mounted on a shaft 17 which has a sprocket 18 that is connected by a chain 19 to a sprocket 20 that is carried by the stub shaft 21 of the gear train I.

The cam 16 and the Geneva gear H are driven in timed relation to each other so that at each

step of movement one of the spindles C is presented at the station to which the necks are fed, and at the end of said step of movement or in the interval between steps of movement the cam 16 permits the ejector bar 10 to be drawn downwardly by the spring 11 with a snap action so as to strike the lowermost neck 2 and drive it past the detent 8 out of the chute and to the neck-applying device F. These neck applying devices F include a tubular member 22 which is longitudinally reciprocable in the housing 7 transversely of the discharge openings 5 and 6 of the chute 4. The member 22 has a lateral passage 23 through which each neck 2 may pass into the member, and a pair of diametrically opposite spring arms 24 are mounted in slots 240 in the member 22 to grip and hold the neck as it is ejected from the chute as clearly shown in Figures 7 to 10 inclusive, the passage 23 and spring arms 24 thus serving as a holder for the necks. A guide block 220 secured in the housing 7 is arranged in a groove 221 in the member 22 to prevent rotation of the latter.

The member 22 has a flange 25 to abut the housing 7 for limiting movement of said member in the direction toward the carrier B and this flange has openings 26 in each of which one end of one arm 24 is secured by a set screw 27. The tubular member is located so as to be coaxial or in direct alignment with the spindle C as the latter stops at the first station.

Longitudinally slidably mounted within the tubular member 22 is a push rod 28 which normally is disposed at the side of the passage 23 opposite the carrier B. The tubular member and the push rod are relatively movable longitudinally, such movement being limited by a set screw 29 in the member 22 which has its end in a slot 30 in the push rod. A compression spring 31 is interposed between the tubular member 22 and the push rod for holding them in their normal relation as shown in Figure 4 and to cause them initially to move together and permit relative movement thereof.

The push rod has one end connected to a reciprocable actuator 32, the connection between the push rod and the actuator comprising a sleeve 33 clamped between nuts 34 on the push rod and longitudinally slidable in a bushing 35 that is arranged in an opening 36 in the actuator and has a flange 37 at one end abutting one side of the actuator. A flanged plug 38 is screwed into the other end of the bushing for firmly securing the bushing in the actuator. The sleeve 33 has a shoulder 39 between which and the end of the plug 38 is interposed a compression spring 40.

With this construction, it will be noted that the push rod and the actuator may have relative yielding movement, and the push rod and the member 22 also have relative yielding movement.

The actuator 32 is carried by a sliding guide block 41 that is mounted in a horizontal portion 42 of the frame A, and said guide block carries a roller 43 which follows a groove 44 in a cam 45 which is fixed on the shaft 17. A tension spring 46 is connected between the guide block 41 and the frame A to move the former and the actuator 32 in the direction to actuate the neck applying devices F for applying the necks to the collapsible tubes.

With this construction, rotation of the cam 45 will cause reciprocation of the actuator 32.

Each plastic neck 2 has a basal circumferential flange 46 which preferably is roughened or serr-

rated in any suitable manner. The interior surface of the neck is also serrated as at 460.

The outer end of the tubular member 22 comprises a die which has a surface 47 so shaped as to press the outer walls of the socket 1 of the collapsible tube around the basal flange 46 of the neck 2.

In operation of the machine so far described, the operator applies a collapsible tube to each spindle C just prior to the movement of that spindle to the first station for application of the neck. During a step of movement of the carrier, the ejector bar 10 of the neck feeding apparatus E will have forced a neck into the tubular member 22 as shown in Figure 4. When the carrier has moved one of the spindles C with its collapsible tube D into alignment with the tubular member 22, the actuator 32 will be moved to slide the push rod 28 toward the tube D. At the same time the tubular member 22 will be moved with the push rod until the surface 47 of the tubular member engages the edge of the outer wall of the socket 1 of the collapsible tube. Thereupon movement of the member 22 will be interrupted but the push rod will continue to move and force the neck into the socket 1 as shown in Figure 5. The actuator 32 will continue to move in the same direction so that pressure through the spring 31 will be exerted on the tubular member sufficient to cause the surface 47 to swage or press the wall of the socket 1 around the basal flange 46 of the neck as shown in Figures 5 and 9. Thereupon the actuator 32 will be moved in the other direction and the carrier B will start another step of movement and convey the tube D with the neck thereon to the next station where the tube will be operated upon by the element G.

This element comprises a tube 48 mounted in the actuator 32. Specifically, the actuator has an opening 49 therethrough in which a flanged bushing 50 is secured by a set screw 51. The tube 48 is slidably mounted in an opening in the bushing and is adjustable inwardly and outwardly of said opening by a screw 52. The outer end of the tube 48 has a die surface 53 to compress the metal of the wall of the socket 1 into tight contact with the basal flange of the neck, particularly to force the metal into the serrations in the flange and to provide a non-rotative, water tight joint between the neck and the tube, as shown in Figures 11 and 12.

The die 53 is brought into engagement with one tube simultaneously with the application of the neck to the next succeeding tube, as shown in Figure 6. The desired adjustments to effect proper compression of the metal of the collapsible tube by the die 53 may be effected by movement of the tube 48 in the bushing 50 through adjustment of the screw 52.

It will be seen by those skilled in the art that should the operator fail to remove a tube from its spindle C after the neck has been applied, the tube might be presented at the first station and feeding of another neck and operation of the neck applying device F might result in jamming or injury to parts of the machine. To overcome this possibility we propose to utilize means for preventing feeding of a neck from the chute 4 in case a tube having a neck already applied thereto is presented at the first station.

For this purpose we have shown an electromagnetically operated device for holding the ejector bar 10 against neck-ejecting movement and to release said bar for normal operation as a tube having a neck thereon approaches and passes the

first station respectively. The device comprises a solenoid 55 which has a reciprocable core 56 to which is pivotally connected at 57 one end of a link 58 which has a slot to receive the pin 14 on the ejector bar 10. The slot of the link 58 is of such length that when the core 56 of the solenoid is at its lowermost position as shown in Figure 7 the lever 12 and the ejector bar 10 are free for normal operation, while when the core 56 is drawn upwardly as shown by dot and dash lines in Figure 7 the link 58 will prevent swinging of the lever 12 and downward movement of the ejector bar 10. A spring 59 normally draws the core 56 downwardly so that the pin 14 engages a fixed stop 60.

For controlling energization and deenergization of the solenoid 55, we propose to locate a normally open electric switch 61 on a bracket 62 on the frame of the machine so that the switch will be closed by contact therewith of the plastic neck of a collapsible tube on a spindle which is approaching the first station, and connect said switch in circuit with a holding relay 72 and a normally closed electric switch 63 so that the solenoid 55 will be energized as said collapsible tube approaches the first station and will be held energized until the tube has passed said station, after which the solenoid will be deenergized by opening of the switch 63 as by engagement therewith of the spindle C.

More specifically, the switch 61 comprises a casing 64 in which is a contact block 65 mounted on a reciprocable rod 66 which has a hinged connection 67 with a lever 68. The block cooperates with two fixed contact studs 69 and is normally held out of contact therewith by a spring 70. The switch is so located on the bracket 62 that normally the lever 68 will be untouched and the switch will remain open. However, upon approach of a tube having a neck, the neck will press the lever 68 so as to cause contact between the contact block 65 and the studs 69 and thus close the switch.

The switch 63 is similar in structure and comprises a casing 73 in which is a contact block 74 carried by a switch rod 75 which is reciprocable in the casing and is normally influenced by a spring 76 to hold the contact block 74 in contact with fixed studs 77. A lever 78 is pivotally mounted intermediate its ends at 79 on the casing and has one end hinged at 80 to the switch rod 75 and its other end provided with a roller 81 which is disposed in the path of movement of the spindles C. Normally the switch is closed but when a spindle C passes beneath the roller 81 the switch block 74 is pulled out of contact with the studs 77 to open the switch.

The two switches 61 and 63 are connected in circuit with a holding relay 72 of known construction as shown in Figure 15. This relay comprises a solenoid 82 and a reciprocable armature 83 which cooperates with two contacts 84 and 85. As will be seen from the drawing, the switches 61 and 63, the solenoid 55 and the holding relay 72 are connected in circuit so that normally the solenoid is deenergized. When the switch 61 is closed, the holding relay is operated to close and hold closed the circuit through the solenoid 55 and also to maintain the circuit through its own solenoid 82. Then when the switch 63 is opened the circuit is broken and the holding relay solenoid 82 is deenergized so that its armature 83 is actuated by a spring 86 as usual to break the circuit through the solenoid 55.

As above indicated, when the switch 61 is closed

the consequent energization of the solenoid 55 results in a holding of the ejector bar 10 of the neck feeding apparatus against feeding operation, while when the switch 63 is opened, consequent deenergization of the solenoid 55 will release the ejector bar 10 for normal operation.

While we have shown and described the invention as embodied in certain details of structure, it will be understood that many changes in the structure of the machine may be made within the spirit and scope of the invention.

What we claim is:

1. In a machine of the character described, a support for a collapsible tube that has a socket at one end in which a neck is to be secured, a supply chute for such necks having a discharge opening in juxtaposition to the said end of a tube on said support, a tubular member that is longitudinally reciprocable transversely of said discharge opening and has a lateral passage to register with said discharge opening and to receive one of said necks into said member, a push rod within and reciprocable relatively to said tubular member to push said neck out of the latter and into said socket, said tubular member having a die to press the walls of said socket around said neck, and means for actuating said devices in succession.

2. The machine set forth in claim 1 with the addition of spring fingers in said tubular member for releasably gripping and holding a neck as the latter is discharged from said chute into said lateral passage.

3. The machine set forth in claim 1 with the addition of detent means for normally preventing discharge of said necks from said discharge opening of said chute, an ejector for forcing a neck through said discharge opening, and spring arms in said tubular member to releasably grip and hold said neck as it is ejected from said discharge opening into said lateral passage.

4. In a machine of the character described, a support for a collapsible tube that has a socket at one end in which a neck is to be secured, a supply chute for such necks having a discharge opening in juxtaposition to said end of a tube on said support, a tubular member that is longitudinally reciprocable transversely of said discharge opening and has a lateral passage to register with said discharge opening and to receive one of said necks into said member, a push rod within and reciprocable relatively to said tubular member to push said neck out of the latter and into said socket, said tubular member having a die to press the walls of said socket around said neck, means including a compression spring connecting said push rod and said tubular member so that they may move initially together in the direction to push said neck into said socket and thereafter said tubular member may move relatively to said push rod, and a reciprocable actuator connected to said push rod.

5. The machine set forth in claim 4 with the addition of means for moving said support in a certain path step-by-step so that said neck is applied to said socket at the end of one step of movement, and a die carried by said actuator for compressing the walls of said socket of the collapsible tube into tight contact with said neck at the end of a subsequent step of movement of said support.

6. A machine of the character described comprising the combination of a plurality of article supports each to receive an article that has a portion to which a part is to be secured, a car-

rier for moving said supports step-by-step in a certain path in succession to an operating station, means at said station for feeding said parts one by one in timed relation to movement of said supports into juxtaposition to each said article as the latter is presented at said station, means for applying one of said parts to each of said articles during the interval between steps of movement of said carrier, a device for stopping discharge of said parts from said feeding means, and means causing operation of said device when an article having one of said parts thereon is presented at said station including an element adjacent said path of movement in advance of said station to be actuated by contact therewith of said part as the latter is moved toward said station.

7. A machine of the character described comprising the combination of a plurality of article supports each to receive an article that has a portion to which a part is to be secured, a carrier for moving said supports step-by-step in a certain path in succession to an operating station, means at said station for feeding said parts one by one in timed relation to movement of said supports into juxtaposition to each said article as the latter is presented at said station, means for applying one of said parts to each of said articles during the interval between steps of movement of said carrier, said feeding means including a feed control element, and means for preventing and for permitting operation of said feed control element as an article having a part thereon approaches and passes said station respectively, including an element adjacent said path in advance of said station to be actuated by contact therewith of said part as the latter approaches said station, and a second element to be actuated in timed relation to the passing of said station by each support.

8. A machine of the character described comprising the combination of a plurality of article supports each to receive an article that has a portion to which a part is to be secured, a carrier for moving said supports step-by-step in a certain path in succession to an operating station, means at said station for feeding said parts one by one in timed relation to movement of said supports into juxtaposition to each said article as the latter is presented at said station, means for applying one of said parts to each of said articles during the interval between steps of movement of said carrier, said feeding means including a feed control element, and electromagnetically actuated means for preventing and for permitting operation of said feed control element upon energization and deenergization of said means as an article having a part thereon approaches and passes said station, respectively, and means for controlling said electromagnetically operated means including a normally open electric switch adjacent said path in advance of said station to be momentarily closed by contact therewith of said part as the latter approaches said station, a normally closed switch to be momentarily opened by contact therewith of each support as the latter passes said station, and a circuit including said electromagnetically operated means, said switches and a holding relay for maintaining said circuit closed through said electromagnetically operated means during the interval between the closing of the first switch and the opening of the second switch.

9. A machine of the character described comprising the combination of a plurality of dead

spindles each to support a collapsible tube that has a socket at one end in which a neck is to be fitted, a rotatable disc for moving said spindles step-by-step in a certain path to present said tubes in succession at an operating station, means at said station for feeding necks singly in timed relation to movement of said disc into juxtaposition to said end of each tube as the latter is presented at said station including a tubular holder having a lateral passage to receive and position said parts, and mechanism including said holder normally located at the side of said feeding means opposite said tube and movable transversely of said path of movement, said mechanism including a push rod for pushing said neck from one end of said tubular holder into said socket of the corresponding tube and an annular die at said end of said holder for pressing the outer walls of said socket around said neck to attach the neck to the tube, and means for actuating said push rod and said die to cause said pushing and pressing operations in succession in the interval between successive steps of movement of said disc.

10. A machine of the character described comprising the combination of a plurality of horizontal dead spindles each to support a collapsible tube that has a socket at one end in which a neck is to be fitted, a disc rotatable in a vertical plane and having said spindles projecting horizontally from one face thereof for moving said spindles step-by-step in a certain path to present said tubes in succession at an operating station, means at said station for feeding necks singly in timed relation to movement of said disc into juxtaposition to said end of each tube as the latter is presented at said station including a holder to receive and position said parts, and mechanism including said holder normally located at the side of said feeding means opposite said tube and movable transversely of said path of movement, said mechanism including a push rod for pushing said neck from said holder into said socket of the corresponding tube and an annular die for pressing the outer walls of said socket around said neck to attach the neck to the tube, and means for actuating said push rod and said die to cause said pushing and pressing operations in succession in the interval between successive steps of movement of said disc, said die being telescopically fitted over said push rod and connected thereto so that initially said push rod and said die move together until said neck has been seated in said socket and thereafter movement of said push rod is stopped by abutment of the neck with the base of said socket and said die moves independently of said push rod.

11. A machine of the character described comprising the combination of a plurality of horizontal dead spindles each to support a collapsible tube that has a socket at one end in which a neck is to be fitted, a disc rotatable in a vertical plane and having said spindles projecting horizontally from one face thereof for moving said spindles step-by-step in a certain path to present said tubes in succession at an operating station, means at said station for feeding necks singly in timed relation to movement of said disc into juxtaposition to said end of each tube as the latter is presented at said station including a holder to receive and position said parts, and mechanism including said holder normally located at the side of said feeding means opposite said tube and movable transversely of said path of movement, said mechanism including a push rod for pushing

said neck from said holder into said socket of the corresponding tube and an annular die for pressing the outer walls of said socket around said neck to attach the neck to the tube, and means for actuating said push rod and said die to cause said pushing and pressing operations in succession in the interval between successive steps of movement of said disc, said means for actuating said push rod and said die being a common reciprocable actuator, there being operative connection between said actuator and said push rod, and said die being telescopically fitted over said push rod and connected thereto so that initially said push rod and said die move together until said neck has been seated in said socket and thereafter movement of said push rod is stopped by abutment of the neck with the base of said socket and said die moves independently of said push rod.

12. A machine of the character described comprising the combination of a plurality of article supports each to receive an article that has a portion to which a part is to be secured, a carrier for moving said supports step-by-step in a certain path in succession to an operating station, means at said station for feeding said parts one by one in timed relation to movement of said supports into juxtaposition to each said article as the latter is presented at said station including a holder to receive and position said parts, and mechanism including said holder normally located at the side of said parts opposite said article and movable transversely of said path of movement of said supports and including a device to push each part from said holder onto said portion of the corresponding article and a second device for pressing said part and said portion into snug contact with each other, said devices initially being movable together and the latter being movable relatively to the former after the pushing operation, and a common reciprocable actuator for actuating said devices to cause said pushing and pressing operations in succession at the end of each step of movement of said carrier, said devices being telescopically associated and there being an operative connection between one thereof and said actuator, and the other of said devices being connected to the first-mentioned device for yielding relative movement.

13. A machine of the character described comprising the combination of a plurality of article supports each to receive an article that has a portion to which a part is to be secured, a carrier for moving said supports step-by-step in a certain path in succession to an operating station, means at said station for feeding said parts one by one in timed relation to movement of said supports into juxtaposition to each said article as the latter is presented at said station including a holder to receive and position said parts, and mechanism including said holder normally located at the side of said parts opposite said article and movable transversely of said path of movement of said supports and including a device to push each part from said holder onto said portion of the corresponding article and a second device for pressing said part and said portion into snug contact with each other, and means for actuating said devices to cause said pushing and pressing operations in succession at the end of one step of movement of said supports, said means for actuating said devices including a common reciprocable actuator, an operative connection between said actuator and said devices, a driving shaft, a cam thereon, and a follower for said cam mounted on said reciprocable actuator.

14. A machine of the character described comprising the combination of a plurality of article supports each to receive an article that has a portion to which a part is to be secured, a carrier for moving said supports step-by-step in a certain path in succession to an operating station, means at said station for feeding said parts one by one in timed relation to movement of said supports into juxtaposition to each said article as the latter is presented at said station, including a holder to receive and position said parts, and mechanism including said holder normally located at the side of said parts opposite said article and movable transversely of said path of movement of said supports and including a device to push each part from said holder onto said portion of the corresponding article and a second device for pressing said part and said portion into snug contact with each other, and means for actuating said devices to cause said pushing and pressing operations in succession at the end of one step of movement of said supports, said means for actuating said devices includes a common reciprocable actuator an operative connection between said actuator and said devices, a driving shaft, a cam thereon, and a follower for said cam mounted on said reciprocable actuator, and said means for feeding said parts includes a feed control element, a second cam on said shaft, and an operative connection

between said second cam and said feed control element.
